PAUL H. OLSON, OF ST. PAUL, MINNESOTA

HOT-WATER BOILER

Application filed April 8, 1925. Serial No. 21,500.

The present invention relates to heating plants, and more particularly to a boiler for use therein.

In heating the water for use in a heating plant, it is desirable to pass the heated gases from a source of heat such as a bed of coal over a large area of water containing compartments before the gases are discharged into a stack, and to do this with a minimum 10 interference with the passage of the gases from the heating element to the stack. Furthermore, it is desirable to keep the amount of water contained in the boiler as small as possible, in accordance with the well known 15 principle that a given amount of water will heat more rapidly in a broad, shallow pan than it will in a deep cup of small diameter.

An object of the present invention is to 20 make a boiler having water compartments therein, said water compartments being positioned to lie in the path of upwardly passing heated gases therein, and to alternately spread and converge said gases in an upward passage through said boiler.

Another object is to make a boiler having 25 a plurality of double conical shaped chambers therein with water compartments of a size to fit within such compartments to cause upwardly passing gases from a heating element therein to pass over a large portion of the surfaces of said compartments.

In order to attain these objects, there is provided, in accordance with one feature of the invention, a boiler having a fire pot with a 30 water jacket surrounding said fire pot, and a water compartment of shallow, double conical shape positioned above the fire pot and in open communication with the water jacket surrounding said fire pot. A second compartment of double inverted, truncated conical shape, is positioned above said compartment and in spaced relation therefrom, said second compartment being in open communication with the first compartment to allow for a free 35 passage of water therebetween.

Other compartments, as desired, having alternately the shape of the first and of the second mentioned compartments, may be placed above said compartments in spaced 40 relation thereto, as required.

These and other features of the invention, not specifically mentioned, will be more fully brought out in the following description and the accompanying drawings, wherein:

Figure 1, is a view, partly in vertical section, and partly in front elevation, of a boiler made in accordance with the present invention; and

Figure 2, is a view in top elevation of a water compartment to be mounted within 55 said boiler, showing inter-connecting pipes mounted thereon

Referring to the drawings in detail, a boiler is shown having a base A of a well known type of construction, shown in front elevation, an 60 upper portion B being shown in vertical section. The boiler is built up of assembled units, and comprises a fire pot section 1 having a water jacket 2 extending around it with the exception of a feed door opening, not 65 shown, which may be of a well known type of construction in hot water and similar boilers. A water compartment 3 forms a closure across the top of the fire pot with the exception of 70 flue openings 4, which permit the upward passage of heated gases from the fire pot. The compartment 3 is in open communication with the water jacket 2 by means of trough-like channels 5, a portion of the left hand one being illustrated as broken away to show the 75 opening 6 thereof into the water jacket. The provision of the trough-like channels permit sediment present in the water to drain off into the water jacket from which it may be periodically flushed, if desired, and carried off through openings 7 which are for the purpose of receiving return pipes when the boiler 80 is used as a hot water or steam plant.

Positioned upon the fire box section is a second section 9 supported thereon by connections 12, which may be nipples having threaded connection with the sections 9 and 3. A rim 10 of metal may be secured in place after the sections are connected to form a gas-tight seal between the compartment 9 and 85 the water jacket 2 and may be provided with a clean-out door, not shown, of a type commonly employed in boilers of this character. This second section is formed in the shape of 90 two inverted, truncated cones, which are in- 100

terconnected by means of a cylindrical section 11. Above the second section and in spaced relation thereto, a compartment 13 is positioned upon other pipes 12, this compartment having the shape of two broad, shallow cones interconnected around the circumferences of their bases. Other compartments similar to compartment 9 and compartment 13 may be positioned one above the other, as desired, one only of each being shown in the present illustration.

A top compartment 14, has its lower surface shaped similarly to the lower surface of compartment 9 and is finished off on the top in a manner well known in boiler construction. A surrounding rim 15 similar to rim 10 is positioned to seal the space between the edges of compartments 9 and 14. Outlet openings 16 and 17 are provided to permit water heated in the boiler to flow out into a heating system with which the boiler is intended to be used.

It will be noted, in positioning the pipes interconnecting the sections, that one pair is shown placed near the periphery of the compartments and one pair near the center thereof. This is for the purpose of providing a water outlet near the upper part of each compartment to permit the upward flow therethrough of the heated water, and also to provide a pipe near the lower portion of each compartment to permit the downward passage therethrough of sediment contained in the water and thereby prevent said sediment from collecting in the bottom of each compartment, to act as an insulation against the influx of heat therethrough.

A boiler of the type herein described is very efficient, since, by alternately spreading the heated gases outwardly and then converging them, the gases are made to pass over a large amount of heating surface. The fact that the compartments are relatively shallow also reduces greatly the amount of water contained in each compartment. The passages for the heated gases all slope upwardly and this construction offers a minimum interference with the upward passage of the gases and thereby greatly increase the efficiency of operation of the boiler.

While the invention has been described and illustrated as embodied in a cast iron construction for use in a hot water heating plant or low pressure steam plant, it is to be understood that the compartments may be made of sheet metal, such as sheet aluminum, for use in a garage or incubator heater, or a heater for running water, and that where thus employed, a gas flame may be substituted for the coal fire illustrated and the water jacket sur-

rounding the heating element may be in that case dispensed with. The return pipe or supply pipe, as the case may be, in that case would be positioned to enter near the bottom of the lower compartment herein designated 3.

What I claim is:

1. A boiler of the character described having a combustion chamber, distinctly separate compartments respectively of double-convex and double-concave configuration, alternately arranged in spaced superposed relation above the combustion chamber, elements enclosing the spaces between the compartments to provide circulation spaces as compartments between adjacent compartments, connections establishing communication between the interior of the compartments, and other connections establishing continuous communication between the spaces between the compartments and the combustion chamber, and means for delivering fluid to connected compartments, the arrangement being such that the lower floors of some of the compartments slant downwardly and outwardly and others downwardly and inwardly, and the circulation interconnection being such that the loosened soot, ash or scale will continuously flow or travel by gravity through respectively interconnected types of compartments towards the lowest portion of the system. 70 75 80 85 90

2. A boiler of the character described, having a combustion chamber, a plurality of alternate, double convex and double concave water compartments in vertically spaced relation from one another, and from the combustion chamber, each of the double concave compartments having gas passages centrally thereof and each of the double convex compartments having gas passages adjacent the outer edges thereof, and water conducting nipples inter-connecting each of said compartments with the one next vertically adjacent thereto. 95 100

3. A boiler of the character described, having a combustion chamber, a plurality of alternate double convex and double concave water compartments in vertically spaced relation from one another and from the combustion chamber, the double convex compartments being of smaller diameter than the double concave compartments, and water conducting flues connecting a point near the bottom of each of said compartments with a point substantially midway of the depth of the next lower compartment, and connecting a point near the top of each compartment with a point substantially midway of the height of the next compartment above it to provide a maximum flow of water upwardly therethrough and to permit the passage of particles heavier than water downwardly therethrough to provide a maximum circulation with a minimum deposit of foreign substances in the compartments. 105 110 115 120

4. In a boiler of the character described, a plurality of superposed interconnected compartments, said compartments being alternately of double conical concave and double conical convex shape, all of the compartments having their sides positioned at sub- 125 130

stantially the same slope with respect to their base, the double conical concave compartments having an aperture centrally thereof, a double conical convex compartment being positioned substantially centrally intermediate each superposed pair of double conical concave compartments, and the double conical convex compartments being of smaller diameter than the double concave compartments.

5. In a boiler of the character described, a plurality of superposed interconnected compartments, said compartments being alternately of double concave and double convex shape, the concavity of each of the first mentioned compartments being substantially the same as the convexity of each of the second mentioned compartments, the concave compartments each having a central aperture therethrough, and the convex compartments being positioned substantially centrally intermediate each pair of concave compartments, and means inter-connecting each compartment with the compartment next vertically adjacent thereto, one of said means being in open communication at a point near the top of each compartment with a point spaced downwardly from the top of the next higher compartment and from a point adjacent the bottom of each compartment with a point spaced downward from the top of the next lower compartment.

In testimony whereof I affix my signature.
PAUL H. OLSON.
